US00D872403S

(12) **United States Design Patent** (10) Patent No.: **US D872,403 S**
(45) Date of Patent: ** Jan. 7, 2020

(54) **TRIGGER GRIP**

(71) Applicant: **Unger Marketing International, LLC**,
Bridgeport, CT (US)

(72) Inventors: **William Harrington**, Charlestown, RI
(US); **John A. Triunfo, Jr.**, Fairfield,
CT (US); **Robert F. Smith**, Waterbury,
CT (US)

(73) Assignee: **UNGER MARKETING
INTERNATIONAL, LLC**, Bridgeport,
CT (US)

(**) Term: **15 Years**

(21) Appl. No.: **29/574,540**

(22) Filed: **Aug. 16, 2016**

Assistant Examiner — John R Yeh

(74) Attorney, Agent, or Firm — Cantor Colburn LLP

(57) **CLAIM**

The ornamental design for a trigger grip, as shown and described.

DESCRIPTION

FIG. 1 is a front, top left perspective view of a trigger grip; FIG. 2 is a front, top right perspective view of the trigger grip thereof;

FIG. 3 is a front, bottom left perspective view of the trigger grip thereof;

FIG. 4 is a front, bottom right perspective view of the trigger grip thereof;

FIG. 5 is a left side view of the trigger grip thereof;

FIG. 6 is a front view of the trigger grip thereof;

FIG. 7 is a right side view of the trigger grip thereof;

FIG. 8 is a top view of the trigger grip thereof; and,

FIG. 9 is a bottom view of the trigger grip thereof.

The broken lines are for the purpose of illustrating structure that forms no part of the claimed design.

1 Claim, 6 Drawing Sheets
